UNITED STATES PATENT OFFICE.

ANSEL C. HULBERT, OF SAN FRANCISCO, CALIFORNIA.

DESIGN FOR AN ELECTRIC STEAM-RADIATOR.

47,039.

Specification for Design.

Patented Mar. 2, 1915.

Application filed September 16, 1914. Serial No. 862,115. Term of patent 7 years.

To all whom it may concern:

Be it known that I, ANSEL C. HULBERT, a citizen of the United States, residing at San Francisco, in the county of San Francisco and State of California, have invented a new, original, and ornamental Design for Electric Steam-Radiators, of which the following is a specification, reference being had to the accompanying drawing, forming part thereof.

The figures illustrate different views of the radiator, Figure 1 being a perspective view of the front of the radiator, while Fig. 2 is a perspective view of the radiator looking at the back thereof.

Copies of this patent may be obtained for five cents each, by addressing the "Commissioner of Patents, Washington, D. C."

What I claim is—

The design for an electric steam radiator substantially as shown in the drawing annexed hereto.

In testimony whereof I have hereunto set my hand this 10th day of September, A. D. 1914, in the presence of the two subscribed witnesses.

ANSEL C. HULBERT.

Witnesses:

C. P. GRIFFIN,
HENRY B. LESTER.
